(57) **CLAIM**

The ornamental design for a carriage, as shown and described.

DESCRIPTION

FIG. 1 is a perspective front view of a baby carriage with seat showing our new design;

FIG. 2 is a perspective rear view of the carriage shown in FIG. 1;

FIG. 3 is a perspective top view of the carriage shown in FIG. 1;

FIG. 4 is a left side view of the carriage shown in FIG. 1;

FIG. 5 is a right side view of the carriage shown in FIG. 1;

FIG. 6 is a left, front perspective view of the carriage shown in FIG. 1;

FIG. 7 is a left, rear perspective view of the carriage shown in FIG. 1; and,

FIG. 8 is a bottom view of the carriage shown in FIG. 1. Broken-line disclosure is understood to represent portions of the article in which the claimed design is embodied, but which form no part of the claimed design.
